US0D1068819S

(12) **United States Design Patent** (10) Patent No.: **US D1,068,819 S**
Pohl et al. (45) Date of Patent: ** Apr. 1, 2025

(54) **DISPLAY SCREEN OR PORTION THEREOF WITH GRAPHICAL USER INTERFACE**

(71) Applicant: **CELUS GmbH**, Munich (DE)

(72) Inventors: **Alexander Pohl**, Heldenstein (DE); **André Pesco Alcalde**, Munich (DE); **Gülce Kurucay**, Munich (DE)

(73) Assignee: **CELUS GmbH**, Munich (DE)

(**) Term: **15 Years**

(21) Appl. No.: **29/964,120**

(22) Filed: **Sep. 20, 2024**

Related U.S. Application Data

(63) Continuation of application No. 18/449,549, filed on Aug. 14, 2023.

(51) **LOC (15) Cl.** **14-04**

(52) **U.S. Cl.**

USPC **D14/485**

CPC **G06F 16/24578** (2019.01); **G06F 30/31** (2020.01)

(58) **Field of Classification Search**

USPC **D14/485-495**

CPC **G06F 3/048; G06F 3/0481; G06F 3/04817; G06F 3/0482; G06F 3/0483; G06F 3/04842; G06F 3/0485; G06F 3/04855; G06F 3/0486; G06F 3/0488; G06F 3/04886; G06F 9/451; G06Q 10/10; G06Q 50/01; H04N 21/4312; H04N 21/4438; H04N 21/47; H04N 21/4788; H04N 21/482; H04L 51/52; H04L 41/22**

(57) **CLAIM**

The ornamental design for a display screen or portion thereof with graphical user interface, as shown and described.

DESCRIPTION

The FIGURE is a front view of a display screen or portion thereof with graphical user interface showing our new design.

The broken lines showing a display screen or portion thereof form no part of the claimed design.

1 Claim, 1 Drawing Sheet

» Info Specs

Name **RED LED THT Round 5mm**

Short Info **RED LED in a THT Round 5mm pack**

[Full Info](#)

A LED with red color and packaged into THT Round 5mm size,already having current-limiting resistor

Category **Optoelectronics**

Sub-Category **LEDs & Lighting**

Sub-Category **LEDs**

Sub-Category **Single Color LEDs**
